BUTTER CUTTER

Carl R. Wahlstrom and Charles G. Wahlstrom,
Redwood City, Calif.

Application January 15, 1941, Serial No. 374,576

7 Claims. (Cl. 31—20)

The invention has for an object to provide a device for slicing butter into small pieces suitable for individual servings, as well as adaptable to larger pieces, and is especially adapted in the present instance to receive the standard, one-pound brick of butter to operate thereon to slice individual servings from the brick by very simple operations.

It is an aim of the invention to present such a device which is adapted to slice particles of butter from a block or brick in appropriate sizes for individual servings, or for larger servings, if desired. An important further object of the invention is to present a novel construction in means for feeding a butter brick past a slicing position and at the same time operate a slicing device in an efficient and simple manner. A further important aim of the invention is to provide a novel means for varying the thickness of the slice in a given machine at will.

A further important aim of the invention is to present such a device which may be constructed at a comparatively small cost, and which will be liable in a minimum degree to derangement or impairment of function incident to ordinary uses. A further important object of the invention is to present a mechanism which will be liable in a minimum degree to accumulation of dirt which would foul its operation, or soil the butter.

An especially important aim of the invention is to present such a device which may be used as a butter container, which may be placed in a refrigerator or the like, with the butter contained therein, and operated as required to slice off and discharge servings of butter as required.

A further important object of the invention is to present such a device which will keep the butter entirely enclosed, when desired, without special manipulation of closure devices and for other purposes.

Additional objects, advantages and features of invention reside in the construction, arrangement and combination of parts involved in the embodiment of the invention, as will be more readily understood from the following description and accompanying drawing, wherein

Figure 1 is a perspective view of the device in open position, ready to receive a butter brick.

Figure 2 is a longitudinal sectional view thereof, with a butter brick in place, ready for the first slicing operation.

Figure 3 is a top view of the device, partly in section,

Figure 4 is a cross sectional view on the line 4—4 of Figure 2.

Figure 5 is a fragmentary view of the feeder band.

Figure 6 is a fragmentary perspective view of the article with a modified blade construction.

Figure 7 is a detail of the blade in one-form.

There is illustrated a butter slicing device adapted to be produced in metal by various methods well understood in manufacture of articles of this nature, and including in the present instance a box-like housing or case 10, including an upper or cover portion 11, substantially U-shaped in cross section, and a removable bottom 12. The case and bottom form a rectangular receptacle, open at the forward or left hand end as viewed in Figures 1 and 2, the cover 11 having an end wall 13 at the inner end. The front or discharge end of the case, which is at the left in the figures mentioned, is formed with smoothly finished surfaces in a plane, which is inclined upwardly and forwardly to the right, for a special purpose which will be made plain in the subsequent description. The bottom stops short of the rear wall 13, and a complementary rear bottom portion 14 is formed integrally with the upper case portion, as shown. This rear bottom portion 14 will also include two legs or other support elements 15, while the removable bottom portion 12 may include corresponding legs or other supports 16 adjacent the forward end. The space within the case as defined by its top and side walls and bottom 12 is rectangular in cross section and of a size slightly greater than that of the standard one-pound butter brick now commonly marketed throughout this country, and the length of the space within the case cover is sufficiently greater than the length of the standard butter brick to accommodate a pusher or follower 17 which is longitudinally reciprocable within the case, resting upon the bottom 12 as shown, and being of sufficient size to properly force a block of butter forwardly from within the case, as will appear hereinafter. The bottom 12 and the portion 14 are formed with an undercut channel 18, and the follower 17 is formed with a central downwardly projecting rib 19 which engages slidably in the narrow entrance to the channel, and is attached to a broad pusher strap 20 of metal of suitable material, which is slidable in the channel. It is formed with a series of saw-teeth serrations 21, on one edge, directed rearwardly for engagement by a feeder device to be subsequently described. The pusher strap is of highly flexible material, and may consist of a short section of band saw. It extends a substantial distance rearwardly of the case, up-

wardly and forwardly into a frame device and feed means, now to be described.

Fixed rigidly on the cover 11, there is a frame structure 22, which is extended rearwardly of the case a short distance, thence upwardly and curved forwardly, to form a stop arm 23, the function of which will be subsequently described, this stop arm extending to a point over the case, a short distance inwardly of its discharge end, as plainly disclosed in Figure 2. Formed in any approved manner in the frame and stop arm, there is a guide channel 24, of a size to receive the pusher strap 20 slidably throughout the length of the channel or as far as required. The stop arm 23 is formed with a slot 25 open through the side, and the extreme end portion of the pusher strap has attached thereto the retractor knob 26, the stem of which is extended through the slot for manual operation as will be described.

The frame includes two side plates 27, one or both of which may be removable, and being shown at the near side and attached by screws 28, as in Figure 1. An operative lever 30 is shown pivoted on one of the plates by means of an eccentric 31 having a shank portion 32 revolvable in the guide plate and provided with a wing head 33, by which it may be rotated to change the axis of the lever pivot as may be desired, for purposes to be made plain hereafter. On the body of the frame between the plates 27, a spring seat lug 34 is provided, while at a distance therefrom the lever 30 is provided with a shoulder 35 above the lug 34, and confined between the two there is a compression spring 36. The spring 36 serves to hold the lever 30 yieldingly in initial position as shown in Figure 2, yieldable to manual operation to lift the lever, for operation as will be described. The lever is formed with an extension 37 at its lower side, on which there is fixed a spring blade 38, extended through a suitable slot in the frame-work, which slot extends under the toothed edge of the pusher strap 20, and also laterally beyond the strap, so that the blade 38 may move beside the strap 20 in one direction, freely, the blade being provided with an inturned edge 39 adapted to engage the teeth 21 of the strap 20, so as to push the latter forwardly in the case, on raising movement of the lever 30, as will be understood. The blade 38 extends a distance outwardly of and below the strap 20, and is formed with a lateral extension 40, projected beyond the side of the frame at its rear part, and formed with a push-button 41 by which it may be manually operated to press the blade 38 away from the strap 20 at times, to permit return of the strap to initial position as will hereinafter appear.

The forward end of the lever 30 is formed with a pivot knuckle 42, which is fitted snugly between the upstanding ears 44 on a blade mounting and closure 45. The pivot axis of this device is closely adjacent the upper forward extremity of the case, although its location need not be fixed with great exactness, with respect to this end of the case. The blade mounting includes a plate portion 46 which extends downwardly to or near the level of the bottom 12, and is of an extent to completely equal the transverse area of the case and integral side plates 47 from which the ears 44 are projected, the plates 47 being adapted to pass on each side of the side walls of the cover 11 freely, and to extend slightly to the rear of the end edges 48 of the case, which have the peculiar inclination before referred to. A butter-slicing blade 49 is fixed between the

plates 47, and include a portion adapted to rest slidably against the edges 48 slightly below the flat face of the bottom 12 when the lever 30 is in lowered position. The blade mounting also includes an upper rearwardly extending arm 50, disposed at such an angle to the radius of the blade 49 with respect to the pivot of the blade mounting that the arm 50 will engage the top of the case, and be pressed upwardly, so as to swing the blade 49 rearwardly against the edges 48 when the lever 30 is fully lowered. The arm 50 is provided with an upwardly extended tongue 51, engaged slidably through a slot in the lever 30, a friction device 52 being mounted on the lever to engage the tongue 51 and hold it yieldingly at its respective limits of movement in the course of operation of the device, as will be explained. The tongue is extended upwardly, so that when the lever 30 is lifted to its upper limit of movement, the tongue will engage the under side of the extremity of the stop arm 23 and be pressed downwardly slidably through the lever 30, so as to swing the plate 46 and the blade 49 forwardly to an open and clearing position where they will be held by the friction device 52 until return of the lever 30 to its lowermost position, when the arm 50 will again move the blade to its rearmost position. The upward movement of the lever 30 is limited by means of an adjustable screw 53 engaged in the upper side of the lever 30 and arranged to engage the under side of the stop arm 23 when the lever is raised. Adjustment of the screw to vary its projection above the lever will determine the opening movement of the blade mounting by means of engagement of the tongue 51 with the stop arm 23, as will be readily understood. It should also be appreciated that the friction device 52 will cause the blade 49 to press rearwardly against the edges 48 as the lever 30 is raised, so as to cause the blade to ride upon these edges 48 throughout lifting movement of the lever. Preferably, the tongue 51 engages the arm 23 after the blade 49 has moved above the opening from the case 10, for reasons that will appear.

It will be appreciated that when the cam device is rotated to present it at its lowermost position as dotted in Figure 2, the pivot axis of the lever 30 being lowered, the arc of movement of the blade 38 immediately adjacent the pusher strap will be much shorter for a given operating movement of the lever 30 than when the cam 31 is at its uppermost position, as shown in dotted lines in Figure 2, so that in the latter position, a greater length of strap will be projected forwardly on each operation of the lever than would be the case when the cam is at its lowermost position. By this means, the feed of the strap forwardly may be varied, so as to produce different thicknesses of slices by the operation of the blade 49, as will be described. The blade 49' may be a simple wire, or a flat blade, or may be a zig-zag blade, such as shown in Figures 6 and 7, wherein the blade mounting 45', and other details of the device are the same as previously described, excepting that the upper plate 46 is omitted for the purposes of illustration, or may be omitted in order to afford a greater clearance for the end of the butter brick.

The bottom 10 may be retained in position on the case by any suitable means, but in the present instance, is shown as provided with friction fingers 55 at each side, although other fastenings may be employed if desired.

In the operation of the device, the lever 30 is

moved to fully raised position, slightly above the position illustrated in Figure 1, and in that movement the tongue 51 engages the stop arm 23, swinging the blade mounting forwardly so that the blade is moved a distance forwardly of the case so as to clear the end edges 48. A butter brick may then be removed from the usual carton and inserted slidably in the open end of the case, or the bottom 12 may be pulled downwardly and the brick laid within the cover portion 11 whereupon the bottom 12 is replaced to hold the brick in place. At this time the follower device 17 is at the rear limit of its movement in the case, which is preferably forwardly of the joint between the rear end of the bottom 12 and the forward edge of the bottom portion 14, so that the follower does not have to move across this joint.

In order to slice the butter now, the lever 30 is moved downwardly to its lower limit of movement, which is determined by engagement of the arm 50 against the top of the case 10, this resulting in swinging the blade 49 to its rearmost position against the edges 48 as shown in Figure 2. The spring 36 serves to effect this movement of the lever 30, and for introduction of the butter, the lever 30 must be held manually raised, which may be readily done by grasping the lever 30 and the arm 23 between the palm and fingers of one hand, while the butter is inserted through the open end of the case with the other hand.

For slicing the butter, the lever 30 is now operated, by resting the palm upon the arm 23, and pressing against the under side of the lever 30 with the fingers of the same hand, the operation being repeated by repeated opening and clasping of the hand, a slice being cut at each operation. In the operation of the lever 30, as it is drawn upwardly, the blade 38 engages a tooth of the pusher strap and presses the same forwardly, moving the follower so that the butter is pushed out through the open end of the case. The slope of the edges 48 of the end of the case is such that, as the butter is propelled forwardly, the blade moves upwardly through the brick in a plane within the brick which is vertical and parallel to the original end face of the brick, as will be appreciated.

Repeated operation of the device as thus described finally brings the follower 17 to its forward limit of movement, which may be checked by engagement of the knob 26 with the rear end of the slot 25. At this point, in order to prepare the device for reception of another brick, the button 41 is pressed inwardly, clearing the blade 38 from the teeth of the pusher strap, and the knob 26 is then grasped manually and drawn forwardly in the arm 23 until full retraction of the follower 17 is effected.

If desired, a series of blades or other elements 56 may be mounted upon the blade mounting 45, at the lower edge of the closure plate 46, so as to divide the portion removed by the blade 49 into two or more portions, as may be desired.

It should be noted that in case a zig-zag blade is used, as indicated at 49' in Figures 6 and 7, a portion of the blade adjacent each end may be extended rectilinearly transversely of the holder, so as to rest slidily against the edges 48.

While we have described an embodiment of the invention with great particularity, it will be understood that the device may be modified in many particulars, involving changes in construction, arrangement and combination of equivalents, modification of proportions and other expedients dictated by requirements of use and obvious im-

provements, without departing from the spirit of the invention, as more particularly set forth in the appended claims.

We claim:

5. A device of the character described comprising a case having a butter chamber open at one end and including a guide means inclined to the longitudinal axis of the chamber, a follower in the chamber, means to move the follower step-by-step, a blade mounted for movement on said guide means across the said open end of the case and operative connections between said means to move the follower and the blade constructed and arranged to move the blade across the opening while the follower is moved a distance equal to the longitudinal spacing of the guide means at respective positions of the blade, with respect to said case.
10. The structure of claim 1, in which the means to move the follower consists of a channelled guide device extending rearwardly from the case, upwardly and forwardly thereover, a flexible pusher strap slidable in the guide, an operating lever mounted on the case, a ratchet feed connection between the lever and the strap, and an operative connection between the lever and said blade.
15. The structure of claim 1, in which said case is provided with a frame portion extended from its rear end, thence upwardly and thence forwardly over the case, a guide channel in said frame and forward extension, a flexible pusher strap slidable therein connected to the follower, and having a serrated edge, and a lever mounted in the rear extension of the frame having a spring-pressed blade movable beside the strap to engage the teeth on the latter, said lever being extended forwardly, and including a blade mounting having said blade mounted therein, whereby on operation of the lever outwardly from said case, the strap will be pushed forwardly, and said blade drawn across the open end of the case in a transverse plane of a butter mass ejected by the follower.
20. The structure of claim 1, in which said case is provided with a frame portion extended from its rear end, thence upwardly over the case, a guide channel in said frame and forward extension, a flexible pusher strap slidable therein connected to the follower, and having a serrated edge, a lever mounted in the rear extension of the frame having a spring-pressed blade movable beside the strap to engage the teeth on the latter, said lever being extended forwardly, and including a blade mounting having said blade mounted therein, whereby on operation of the lever outwardly from said case, the strap will be pushed forwardly, and said blade drawn across the open end of the case in a transverse plane of a butter mass ejected by the follower.
25. The structure of claim 1, in which said case is provided with a frame portion extended from its rear end, thence upwardly over the case, a guide channel in said frame and forward extension, a flexible pusher strap slidable therein connected to the follower, and having a serrated edge, a lever mounted in the rear extension of the frame having a spring-pressed blade movable beside the strap to engage the teeth on the latter, said lever being extended forwardly, and including a blade mounting having said blade mounted therein, whereby on operation of the lever outwardly from said case, the strap will be pushed forwardly, and said blade drawn across the open end of the case in a transverse plane of a butter mass ejected by the follower.
30. The structure of claim 1, in which said case is provided with a frame portion extended from its rear end, thence upwardly over the case, a guide channel in said frame and forward extension, a flexible pusher strap slidable therein connected to the follower, and having a serrated edge, a lever mounted in the rear extension of the frame having a spring-pressed blade movable beside the strap to engage the teeth on the latter, said lever being extended forwardly, and including a blade mounting having said blade mounted therein, whereby on operation of the lever outwardly from said case, the strap will be pushed forwardly, and said blade drawn across the open end of the case in a transverse plane of a butter mass ejected by the follower.
35. The structure of claim 1, in which said case is provided with a frame portion extended from its rear end, thence upwardly over the case, a guide channel in said frame and forward extension, a flexible pusher strap slidable therein connected to the follower, and having a serrated edge, a lever mounted in the rear extension of the frame having a spring-pressed blade movable beside the strap to engage the teeth on the latter, said lever being extended forwardly, and including a blade mounting having said blade mounted therein, whereby on operation of the lever outwardly from said case, the strap will be pushed forwardly, and said blade drawn across the open end of the case in a transverse plane of a butter mass ejected by the follower.
40. The structure of claim 1, in which said case is provided with a frame portion extended from its rear end, thence upwardly over the case, a guide channel in said frame and forward extension, a flexible pusher strap slidable therein connected to the follower, and having a serrated edge, a lever mounted in the rear extension of the frame having a spring-pressed blade movable beside the strap to engage the teeth on the latter, said lever being extended forwardly, and including a blade mounting having said blade mounted therein, whereby on operation of the lever outwardly from said case, the strap will be pushed forwardly, and said blade drawn across the open end of the case in a transverse plane of a butter mass ejected by the follower.
45. The structure of claim 1, in which said case is provided with a frame portion extended from its rear end, thence upwardly over the case, a guide channel in said frame and forward extension, a flexible pusher strap slidable therein connected to the follower, and having a serrated edge, a lever mounted in the rear extension of the frame having a spring-pressed blade movable beside the strap to engage the teeth on the latter, said lever being extended forwardly, and including a blade mounting having said blade mounted therein, whereby on operation of the lever outwardly from said case, the strap will be pushed forwardly, and said blade drawn across the open end of the case in a transverse plane of a butter mass ejected by the follower.
50. The structure of claim 1, in which said case is provided with a frame portion extended from its rear end, thence upwardly over the case, a guide channel in said frame and forward extension, a flexible pusher strap slidable therein connected to the follower, and having a serrated edge, a lever mounted in the rear extension of the frame having a spring-pressed blade movable beside the strap to engage the teeth on the latter, said lever being extended forwardly, and including a blade mounting having said blade mounted therein, whereby on operation of the lever outwardly from said case, the strap will be pushed forwardly, and said blade drawn across the open end of the case in a transverse plane of a butter mass ejected by the follower.
55. The structure of claim 1, in which said case is provided with a frame portion extended from its rear end, thence upwardly over the case, a guide channel in said frame and forward extension, a flexible pusher strap slidable therein connected to the follower, and having a serrated edge, a lever mounted in the rear extension of the frame having a spring-pressed blade movable beside the strap to engage the teeth on the latter, said lever being extended forwardly, and including a blade mounting having said blade mounted therein, whereby on operation of the lever outwardly from said case, the strap will be pushed forwardly, and said blade drawn across the open end of the case in a transverse plane of a butter mass ejected by the follower.
60. The structure of claim 1, in which said case is provided with a frame portion extended from its rear end, thence upwardly over the case, a guide channel in said frame and forward extension, a flexible pusher strap slidable therein connected to the follower, and having a serrated edge, a lever mounted in the rear extension of the frame having a spring-pressed blade movable beside the strap to engage the teeth on the latter, said lever being extended forwardly, and including a blade mounting having said blade mounted therein, whereby on operation of the lever outwardly from said case, the strap will be pushed forwardly, and said blade drawn across the open end of the case in a transverse plane of a butter mass ejected by the follower.
65. The structure of claim 1, in which said case is provided with a frame portion extended from its rear end, thence upwardly over the case, a guide channel in said frame and forward extension, a flexible pusher strap slidable therein connected to the follower, and having a serrated edge, a lever mounted in the rear extension of the frame having a spring-pressed blade movable beside the strap to engage the teeth on the latter, said lever being extended forwardly, and including a blade mounting having said blade mounted therein, whereby on operation of the lever outwardly from said case, the strap will be pushed forwardly, and said blade drawn across the open end of the case in a transverse plane of a butter mass ejected by the follower.
70. The structure of claim 1, in which said case is provided with a frame portion extended from its rear end, thence upwardly over the case, a guide channel in said frame and forward extension, a flexible pusher strap slidable therein connected to the follower, and having a serrated edge, a lever mounted in the rear extension of the frame having a spring-pressed blade movable beside the strap to engage the teeth on the latter, said lever being extended forwardly, and including a blade mounting having said blade mounted therein, whereby on operation of the lever outwardly from said case, the strap will be pushed forwardly, and said blade drawn across the open end of the case in a transverse plane of a butter mass ejected by the follower.
75. The structure of claim 1, in which said case is provided with a frame portion extended from its rear end, thence upwardly over the case, a guide channel in said frame and forward extension, a flexible pusher strap slidable therein connected to the follower, and having a serrated edge, a lever mounted in the rear extension of the frame having a spring-pressed blade movable beside the strap to engage the teeth on the latter, said lever being extended forwardly, and including a blade mounting having said blade mounted therein, whereby on operation of the lever outwardly from said case, the strap will be pushed forwardly, and said blade drawn across the open end of the case in a transverse plane of a butter mass ejected by the follower.

having said blade mounted therein, whereby on operation of the lever outwardly from said case, the strap will be pushed forwardly, and said blade drawn across the open end of the case in a transverse plane of a butter mass ejected by the follower, resilient means coengaged between the frame and lever, tending to move the lever at its outer end to closed position, said blade mounting including a closure plate to close the end of the case, said lever being movable in alinement with said forward extension of the frame, whereby said extension of the frame will operate as a stop for the lever. 10

6. The structure of claim 1, in which said case is provided with a frame portion extended from its rear end, thence upwardly and thence forwardly over the case, a guide channel in said frame and forward extension, a flexible pusher strap slidable therein connected to the follower, and having a serrated edge, a lever mounted in the rear extension of the frame having a spring-pressed blade movable beside the strap to engage the teeth on the latter, said lever being extended forwardly, and including a blade mounting having said blade mounted therein, whereby on operation of the lever outwardly from said case the strap will be pushed forwardly, and said blade drawn across the open end of the case in a transverse plane of a butter mass ejected by the follower, resilient means coengaged between the frame and lever at its outer end to closed position, said blade mounting including a closure plate to close the end of the case, said lever being movable in alinement with said forward extension of the frame, whereby said extension of the frame will operate as a stop for the lever, said 35

blade mounting having a strike arm extended over the case, means in position to engage said arm on closing movement of the lever to swing said blade to initial operative position, friction 5 means to hold the blade mounting yieldingly at said position, and means positioned to engage said arm at the outer limit of movement of the lever to swing said blade to disengaged and butter-clearing position.

7. A butter-slicing device and the like, comprising a substantially tubular case adapted to receive butter and the like, and having a follower longitudinally slidably therein, said case having a flexible pusher strap extended slidably and longitudinally therein from one end and engaged with said follower, a mounting and guide for said strap extended rearwardly, upwardly and forwardly over said case, said strap being extended in said guide, a lever pivoted in the right portion of said guide, and having a ratchet feed device thereon engaged in said strap, resilient means tending to hold the lever at one limit of its movement, said guide being extended over the lever as a stop for outward movement of the lever, said lever and guide having portions positioned to be grasped in the hands of an operator for operation of the lever by opening and closing of the grip of the operator, said case being open at its end opposite said guide extension, a slicer blade mounted for movement thereacross obliquely with respect to the axis of the case, and operative connection between the outer end of said lever and the blade, for the purposes described. 20 25 30
